LUMINAIRE

Sheldon M. Rutter, Miami, Fla., assignor to American Electric Manufacturing Corporation, Southaven, Miss.

Filed Dec. 1, 1964, Ser. No. 82,861

Term of patent 14 years

(Cl. D48—31)

FIG. 1

FIG. 2

FIG. 3

FIG. 4

FIG. 1 is a side elevational view of a luminaire showing my new design.

FIG. 2 is a top plan view.

FIG. 3 is a front end view.

FIG. 4 is a cross-sectional view taken as on the line IV-IV of FIG. 1.

The dominant features of my design reside in the portions shown in full lines.

I claim:

The ornamental design for a luminaire, as shown and described.
